UNITED STATES PATENT OFFICE.

FRANK COSS, OF GREENCASTLE, INDIANA.

DESIGN FOR A KITCHEN-CABINET.

48,308.

Specification for Design.

Patented Dec. 21, 1915.

Application filed June 5, 1915. Serial No. 32,454. Term of patent 3½ years.

To all whom it may concern:

Be it known that I, FRANK Coss, a citizen of the United States, residing at Greencastle, in the county of Putnam and State of Indiana, have invented a new, original, and ornamental Design for Kitchen-Cabinets, of which the following is a specification, reference being had to the accompanying drawing, forming part hereof.

The single figure of the drawing is a perspective view of a kitchen cabinet, showing my new design; which involves a superstructure having two superposed compartments each of which is closed in front by a vertically sliding flexible curtain, and a base structure which has at one side a compartment which is closed in front by a laterally sliding flexible curtain or door.

I claim:

The ornamental design for a kitchen cabinet, as shown and described.

In witness whereof, I have hereunto set my hand at Indianapolis, Indiana, this twenty-eighth day of May, A. D. one thousand nine hundred and fifteen.

FRANK COSS.
